UNITED STATES PATENT OFFICE.

FREDERIC P. GATES, OF WEST HARTFORD, CONNECTICUT, ASSIGNOR TO THE HART & HEGEMAN MANUFACTURING COMPANY, OF HARTFORD, CONNECTICUT, A CORPORATION OF CONNECTICUT.

SWITCH AND FUSE-PLUG SOCKET.

Application filed January 7, 1927. Serial No. 159,645.

My invention relates particularly to switch structures and fuse-plug sockets for electric ranges, but it will be understood that the combination and arrangement of parts may 5 be used in any place where a fuse-plug socket is connected to a switch structure. One object of the invention is to independently connect the switch structure and the fuse-plug socket to their respective bus-bars.

10 A further object of my invention is to so construct the connection between a fuse-plug socket and a switch structure that the fuse-plug socket may be adjusted to any angle in respect to the socket.

15 In the accompanying drawing:

Fig. 1 is a side view of a switch structure and a fuse-plug socket connected in accordance with my invention;

Fig. 2 is a rear view;

20 Fig. 3 is a view similar to Fig. 1, but showing the socket at an angle in respect to the switch structure;

Fig. 4 is a detached face view of the fuse-plug socket; and

25 Fig. 5 is a detached perspective view of the fuse-plug socket.

The switch structure 1 is of any suitable type, having a body portion 2 of porcelain, or other non-conducting material, recessed 30 at the back for the connections 3 and 4. The connection 3 is electrically attached to a bus-bar 5 by means of a screw 17, and the body portion is held rigidly to the bar by a screw 18 which in the present instance is not an 35 electrical connection.

The connection 4, in the present instance is of flat metal, shaped as shown in Fig. 4.

40 The connection 4 is forked, as at 10, to fit around a projection 11 of the fuse-plug socket 6, and is held in contact with the base of the threaded shell 12 by screws 13, and extends through a slot 14 in the socket and shell as shown in Fig. 5.

45 This connection 4 is preferably curved and bent as at 7 to fit the recess 8 in the back of the body portion 2 and is electrically connected to one terminal of the switch structure by a screw 9.

The terminal 4 is of comparatively thin metal and can be bent to accommodate the 50 socket to the front of an electric range or to a bus-bar 15, or other connection, and when bent to the proper form it is rigid.

In Fig. 1 the faces of the bus-bars 5 and 15 are on parallel planes and in such a position that the plug and switch structure can be connected to the bars without bending the connection 4.

In Fig. 3 the bus-bar 15 is angularly disposed with respect to the bar 5 and the front 60 of a range, and the connection 4 is bent so that the socket will fit against the surface of the bar.

By making the connection in the form substantially as shown, it can be bent to any 65 angle desired to adjust the fuse plug socket in respect to the front of an electric range. The switch structure can be attached to a single bus-bar and the fuse-plug socket can be firmly secured to the switch structure and 70 to another bus-bar or other conductor.

I claim:

1. The combination of a switch structure having a body portion recessed at the back; a bus-bar to which said structure is secured; 75 a fuse-plug socket having a threaded shell; a second bus-bar; a terminal screw connecting the socket to the bus-bar; a flat metallic connection forked at its inner end and extending through an opening in the socket; 80 and screws securing the connection to the shell and socket, the outer end of the connection being curved and bent to fit a recess in the body of the switch structure.

2. The combination of a switch structure 85 having a body portion; a bus-bar to which said structure is secured; a fuse plug socket having a threaded shell and slotted; a terminal screw connecting the socket with a terminal; a flat metallic connection extending through the slot in the socket; and means for securing the connection to the shell and socket, the outer end of the connection being attached to the switch structure.
